CIGARETTE OPENER AND CARRIER

John J. Cobbs, Roanoke, Va.

Application June 10, 1941, Serial No. 397,493

5 Claims.

(Cl. 30—2)

This invention aims to provide a novel means for slitting a package of cigarettes circumferentially, so that the top of the package can be taken off.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in elevation, a device constructed in accordance with the invention;

Fig. 2 is a vertical longitudinal section;

Fig. 3 is a bottom plan;

Fig. 4 is a vertical section taken at right angles to the showing of Fig. 2;

Fig. 5 is a cross section on the line 5—5 of Fig. 2;

Fig. 6 is a longitudinal section wherein the lid is shown opened, the cutting plane being shifted slightly, considered relatively to the cutting plane in Fig. 4;

Fig. 7 is a fragmental vertical section, wherein the slide and the severing blade are shown advanced;

Fig. 8 is a section on the line 8—8 of Fig. 7;

Fig. 9 is a vertical section showing a modification;

Fig. 10 is a section on the line 10—10 of Fig. 9;

Fig. 11 is a side elevation, wherein parts are broken away;

Fig. 12 is a section on the line 12—12 of Fig. 9.

In carrying out the invention as shown in Figs. 1 to 8, there is provided a casing 1, including a box-like body 2, shaped to receive a package 3 of cigarettes, the body having openings 4 which expose the cigarette package.

A lid 5 is connected to the body 2 by a hinge 6, the hinge being spring actuated to open the lid 5, as shown in Fig. 6. The lid 5 is held releasably closed by a spring latch 7 on the body 2, the latch being released from the lid by means of a button 8 which is presented outwardly of the body 2.

A U-shaped carrier 9 fits slidably in the body 2 and receives the cigarette package 3. The side

arms and the bottom of the carrier 9 are provided with inwardly projecting flanges 10 which prevent contact between the cigarette package 3 and the body 2. The arms of the carrier 9 are rounded at their upper ends, as shown at 11, and are a little longer than the cigarette package 3. Consequently, when the lid 5 is closed, as in Fig. 4, the lid will not come into contact with the upper end of the cigarette package, the lid engaging the rounded ends 11 of the arms of the carrier.

An upwardly acting compression spring 12 is held by a securing element 14 on the bottom of the body 2 and exerts a thrust against the bottom of the carrier 9.

As to the operation of the device as thus far described, assuming that the parts are in the positions shown in Figs. 1, 2 and 3, when the button 8 is pressed, the latch 7 is released from the lid 5, and the lid opens to the position of Fig. 6. When the pressure of the lid 5 on the rounded upper ends 11 of the carrier 9 is released, the carrier and the cigarette package 3 rise, responsive to the thrust of the spring 12, the cigarette package being elevated to a position in which a cigarette can be taken readily out of it. The closing of the lid 5 restores the parts to the position of Fig. 2, and does so without exerting pressure on the upper end of the cigarette package, the downward thrust being received by the rounded ends 11 of the side arms of the carrier 9.

A means is provided for slitting the cigarette package 3, circumferentially, a little below its upper end, to permit the removal of the top of the cigarette package before the cigarette package is placed in the carrier 9. That means is shown as being carried by the body 2 of the casing or receptacle 1, but that need not be the case invariably. The case or receptacle constitutes merely one convenient support or mounting for the slitting mechanism.

The slitting mechanism embodies a slide plate 15, mounted to reciprocate on the bottom of the body 1, below the bottom of the carrier 9. The slide plate 15 is adapted to be advanced and retracted through an opening 16 in one of the narrower side walls of the body 2. At its outer end, the slide plate 15 is thinned to form a reduced tongue 17, at the inner end of which is located a shoulder 18, disposed at right angles to the tongue 17. A triangular blade 19 is let into the slide plate 15 and is secured thereto, the blade overhanging the tongue 17, as depicted in Fig. 7. In the bottom of the body 2, an L-shaped

bayonet slot 20 is formed. The slide plate 15 is provided with a headed button 21, mounted to move in the bayonet slot 20 and exposed beneath the bottom of the body 2, as Fig. 4 will show. The bayonet slot is of such length, and is so positioned in the bottom of the body 2 that when the button 21 occupies the lateral portion of the bayonet slot, the shoulder 18 on the slide plate 15 will be disposed flush with the outer surface of the body 2, as shown in Fig. 8. When the button 21 is dislodged from the lateral portion of the bayonet slot 20, the slide plate 15 and the blade 19 are retracted within the body 2, as in Fig. 2, by means of a retractile spring 22, one end of the spring being connected to the slide plate 15, and the opposite end of the spring being anchored on the bottom of the body 2.

The operator advances the slide plate 15 and associated parts to the position of Fig. 8, in which position it is releasably held by the engagement between the button 21 and the lateral portion of the bayonet slot 20. The cigarette package 3 is drawn along the outer surface of the body 2, in contact with the shoulder 18 of the slide plate 15, the end of the cigarette package being engaged by the tongue 17. The blade 19 severs the cigarette package circumferentially, and after it has been severed, the detached top of the package may be removed, the opened package being inserted into the carrier 9, for the dispensing operation hereinbefore set forth.

The slide plate 15 and associated parts are shown in Figs. 1 to 8 as operating at right angles to the longer axis of the body 2, but that is not necessary. The slide plate may work lengthwise of the body 2, as in the construction delineated in Figs. 9 to 12.

In Figs. 9 to 12, the body of the casing is shown at 23, and the carrier appears at 24. The bottom of the body 23 is provided with an upstanding, box-like housing 25, which is open at its bottom, as shown in Fig. 12. One end of a bowed spring 26 rests on the housing 25, the opposite end of the spring rests on the bottom of the body 23, the intermediate portion of the spring engages the bottom of the carrier 24, and the spring constitutes means for elevating the carrier, together with the cigarette package within it, when the lid, such as the part 5 of Fig. 6, is opened.

The slide plate 27 is in the form of an angle member, comprising a short transverse arm 28 and a longer upright arm 29, arranged at right angles to each other. The upright arm 29 works through a slot 30 in the top of the housing 25, inside one of the narrower upright walls of the body 23, as shown in Fig. 9. The outer transverse arm 28 is adapted to be received within the housing 25.

In order to limit the downward movement of the slide plate 27, to the position shown in Fig. 12, the arm 29 of the slide plate is supplied with a slot 31, accommodating studs 32 which are mounted in the body 23, the studs retaining the

slide plate 27 on the body for reciprocation, as well as limiting the downward movement of the slide plate. The transverse arm 28 of the slide plate 27 carries a fixed, laterally projecting blade 33. The slide plate 27 is raised by a spring means, such as a resilient strip 34, having its upper end attached to one edge of the arm 29 of the slide plate, the lower end of the strip being secured to the top of the housing 25.

In order to move the slide plate 27 downwardly, to the position shown in Fig. 12, the arm 29 of the slide plate carries a button 35, exposed on the outside of the body 23 and mounted to move in a longitudinal slot 36 in the body.

By means of the button 35, the slide plate 27 is forced down, against the action of the spring 34, the blade 33 is exposed, and the cutting operation on the cigarette package proceeds as hereinbefore explained. When pressure on the button 35 is released, the spring 34 restores the parts to the position of Fig. 9, the blade 33 and the arm 28 of the slide plate 27 being housed in the part 25.

In either of its forms, the device embodies a satisfactory and efficient container for a package of cigarettes, combined with a means for slitting the package, to remove the top thereof.

What is claimed is:

1. A cigarette package slitter comprising a support having a slot provided at its outer end with an extension, a slide mounted to move on the support, a cutter carried by the slide, spring means for retracting the slide, and a button on the slide and mounted to move in the slot, the button being received in the extension, to hold the slide and the cutter advanced, against the effort of the spring means.

2. A cigarette package slitter constructed as set forth in claim 1, and wherein the slide has a thinned tongue which is overhung by the cutter, the tongue defining a shoulder in the slide, the slot being so positioned that when the button is in the extension, the shoulder will be flush with the outer surface of the support.

3. A cigarette package slitter comprising a support, an L-shaped slide including a first arm located within the support, and a second arm movable to a position external to the support, means assembled with the first arm for mounting the slide for reciprocation on the support, a cutter carried by the second arm, and means for advancing the slide from a place of force application external to the support.

4. A cigarette package slitter constructed as set forth in claim 3, and wherein the support has a housing which receives the second arm and the cutter when the slide is retracted.

5. A cigarette package slitter constructed as set forth in claim 3, and wherein the support has a housing which receives the second arm and the cutter when the slide is retracted, and spring means connected to the first arm and to the housing for retracting the slide.

JOHN J. COBBS.
